UNITED STATES PATENT OFFICE.

MARY M. HAMMOND, OF KANSAS CITY, MISSOURI.

SAMPLE-CASE.

1,280,453.

Specification of Letters Patent. Patented Oct. 1, 1918.

Application filed February 14, 1916. Serial No. 78,284.

To all whom it may concern:

Be it known that I, MARY M. HAMMOND, a citizen of the United States, residing at Kansas City, in the county of Jackson and 5 State of Missouri, have invented a certain new and useful Improvement in Sample-Cases, of which the following is a specification.

My invention relates to improvements in 10 sample cases.

My invention is particularly well adapted for use on sample cases of the hand bag or trunk type having a body provided with a side opening and having a closure for the 15 opening, hinged at its lower edge to the body so as to be swung from an upright closed position to a horizontal open position.

One of the objectionable features possessed by sample cases of this type is that, 20 when the closure lies flat in the open position, when goods are being displayed, it becomes soiled by resting on the floor, and is liable to be stepped upon and injured.

One of the objects of my invention is to 25 provide a sample case of this type with yielding means, as, for example, a suitable spring, which will normally raise the closure from the horizontal open position and force it toward the closed position.

Another object of my invention is to provide an extensible sample case of the general type above referred to, with means by 30 which the spring tension for lifting the closure from the horizontal position may be varied to meet the requirements caused by extending or contracting the sample case.

Still another object of my invention is to provide for the purposes above stated, a novel form of spring, which occupies very 35 little room, is not in the way, may be readily changed as to tension, is durable and efficient, and which may be readily attached to or removed from the sample case.

In the accompanying drawing which 40 illustrates the preferred embodiment of my invention,

Figure 1 is a vertical sectional view of my improved sample case, shown in solid lines in the closed position and in dotted 45 lines in the open position, the closure being, in the dotted position, shown raised from the horizontal.

Fig. 2 is a plan view of my improved sample case shown in the open position 50 illustrated in dotted lines in Fig. 1.

Similar reference characters designate similar parts in the different views.

In the drawing I have illustrated an extensible sample case having a body comprising a lower member 1 having an open top and front side, on which is vertically and slidably mounted an upper member 2, having an open front side and an open upper end adapted to be closed respectively by an extensible closure 3 and a cover 4. 60

The closure 3 comprises two members longitudinally slidably adjustable one upon the other, the lower member of the closure being hinged at its lower edge to the body member 1 adjacent to the lower end thereof. 70

5 designates the axis of the closure 3. One or more torsion springs are secured to the inner sides of the closure 3 and the body member 1 in the following manner: Each torsion spring is provided with a straight 75 portion 6 which is disposed substantially in alinement with the axis 5 of the closure 3. Each spring is provided at its respective ends with an arm 7 and an arm 8, which extend laterally, preferably at right angles to the straight portion 6. The arm 7 is embraced by an eye or staple 9 which is secured to the upper side of the bottom of the body member 1. 80

The other arm 8 is releasably secured to 85 the inner side of the closure 3 by a member 10 pivoted to the closure 3.

The arrangement of the arms 7 and 8 relatively to each other is such that when the closure 3 has been forced to the horizontal 90 position and then released, the spring or springs will swing the closure 3 from the horizontal position toward the closed position. It may be so arranged that the closure will be swung by the springs to the fully 95 closed position, or the arrangement may be such that the closure will be swung by the springs to a position in which it will be partly open, as shown in dotted lines in Fig. 1. In the latter position, the interior of the 100 sample case will be readily accessible, while the closure will be held out of contact with the floor and in a position in which it is not liable to be accidentally trod upon.

When the sample case is fully contracted, less power will be needed to raise the closure 3 than is required when the sample case is fully extended. For this reason, in the extended position, both springs may be employed, and in the fully contracted position 110

of the sample case, if desired, one of the springs may be detached. This may be effected by swinging the member 10 to a position in which it will be disengaged from the arms 8, after which either one or both of the springs may be withdrawn longitudinally from the eyes or staples 9.

I do not limit my invention to the structure shown and described, as modifications, 10 within the scope of the appended claim may be made without departing from the spirit of my invention.

What I claim is:—

In a sample case, a body having an open 15 side, a closure for the open side hinged at

its lower edge to the body, a torsion spring disposed substantially in alinement with the axis of the closure and having two arms extending at right angles and in opposite directions, an eye secured to the body in which one of said arms is releasably engaged, and a securing member pivoted to the closure and releasably engaging the other arm, the spring being arranged to lift the closure from but permitting it to be forced to a substantially horizontal position. 20 25

In testimony whereof I have signed my name to this specification.

MARY M. HAMMOND.
